UNITED STATES PATENT OFFICE.

CARBON P. DUBBS, OF WILMETTE, ILLINOIS, ASSIGNOR TO UNIVERSAL OIL PRODUCTS COMPANY, OF CHICAGO, ILLINOIS, A CORPORATION OF SOUTH DAKOTA.

PROCESS FOR CRACKING OILS.

Application filed February 17, 1921, Serial No. 445,671. Renewed March 24, 1927.

This invention relates to a process for cracking hydrocarbon oils and refers more particularly to an improved process whereby the apparatus may be operated continuously for a greater period of time due to the fact that the carbon accumulation is restricted to a portion of the apparatus which does not hinder the flow of oil in the system or cause clogging or hot spots which so often attend the continuous operation of processes of this type.

Among the salient objects of the invention are to provide a process whereby the oil during conversion is maintained in an enlarged expansion chamber and the greater part of the carbon deposition, which takes place during the cracking of the oil, is restricted to a collection upon vaporization in the expansion chamber, keeping the carbon separate from the outside heated surface of the retort away from the inlet and outlet lines communicating therewith; to provide an apparatus which is easily cleaned and one which is particularly designed for collecting the deposited carbon in the above described manner.

The figure is a side elevation partly in section with parts broken away to more clearly show the details of the apparatus.

Referring to the drawings, the raw oil is introduced to the top of the dephlegmator 1 through an inlet pipe 2 controlled by a valve 3. The oil travelling down through the dephlegmator serves to separate the higher boiling point fractions from the oil vapors, which travel up through the dephlegmator in an opposed direction. The raw oil with its condensate content which it acquires in the dephlegmator collects in the bottom and is drawn off through a line 4 and is directed to the shell still 5 which is mounted above the furnace 6. At the elbow in the line 4 is inserted a pyrometer 7 for the purpose of ascertaining the temperature of the oil at that point. The still 5 has the detachable head 6^a and a cleaning hole 7^a in the opposite end and, in addition, a pressure gauge 8. Within the still is mounted an inclined still plate or shelf 9 which has an upturned end portion 10. This plate or carbon collector may be fixedly riveted or detachably mounted on lugs positioned in the interior of the still. The oil introduced through the line 4 is maintained at a definite level in the still and being heated to a temperature at

which conversion takes place the vapors released will rise through the vapor line 11 and after being dephlegmated by the raw oil will pass off through the line 12 in which a pyrometer 13 is interposed and to a water condenser 14, thence through the line 15 to a receiver 16. The receiver is fitted with the liquid level gauge 17, pressure relief pipe 18 controlled by a valve 19 and liquid draw-off 20 regulated by a valve 21 and a secondary draw-off line 22 controlled by a valve 23. A residuum line 24 controlled by a valve 25 is tapped into the still shell directly above the lower end of the collector plate 9.

With the conversion of the oil in the shell still, there is a substantial separation of free carbon which is usually permitted to collect in the bottom of the still where it causes difficulties due to the fact that it insulates the oil from the heat of the furnace, causing hot spots and often necessitating the shutting down of the apparatus or hindering the operation of the process due to the clogging of heating tubes, draw-off lines or other pipes communicating with the expansion chamber. The collection plate positioned in the interior of the shell still, as shown, affords a collecting surface for this free carbon and keeps the carbon at all times isolated from contact with the outer surface of the still. In addition to this feature, the carbon is prevented from collecting in the bottom of the still where it obstructs free circulation of the oil, reducing the efficiency of the process and lessening the amount of conversion taking place in the apparatus. By positioning a collecting surface of this type inclined slightly toward the residuum line, it is possible to accumulate the greater portion of the precipitated carbon on the surface of this collector plate and flush the same with the heavy residual oil through the residuum line from time to time. The positioning of this plate above the inlet line also serves as a baffle for the incoming oil to be treated and causes the same to travel along the bottom surface of the still where it is subjected to the highest temperature. After travelling the length of the still and being subjected constantly to a cracking temperature the cracked oil will pass around the end of the collector plate in a direction shown by the arrow and flow over the top of the collecting surface where there is expansion surface afforded for the

vaporization of the oil. Here whatever carbon is released in this vaporization will be deposited on the collector plate and will flow off through the residuum line with the residual oil. The still can be easily cleaned by removing either or both of the plates bolted to the ends thereof.

Primarily, it is the temperature to which the oil is heated in the pressure still which governs the percent of that oil which is cracked and this in turn governs the amount of free carbon produced. Keeping the production of carbon down to a certain limit overcomes any substantial amount of carbon settling out of the oil, but leaves practically all of the carbon fluctuating in the oil and in this state it may be continuously carried out of the portion of the apparatus where the conversion of the oil takes place. The portion of the oil cracked along with more or less of the uncracked oil is separated by being vaporized, the uncracked portion being refluxed to the heating zone free from any free carbon therein. It will be recognized that by placing a partition or collecting plate in the lower section of the still in such a manner that when reflux and raw oil is fed in below where the heat is applied, thence continuously flowing to the upper section of the still not in direct contact with the heat of the furnace that there the substantial portion of the conversion will take place. In the upper portion of the still above the partition the oil is vaporized and the residuum with more or less of the carbon flows down the top of the partition and is drawn off through the residuum line. This operation is continued until the upper portion of the still becomes filled with carbon at which time it may be shut down and cleaned.

This apparatus, in addition to other advantages, is economical in fuel combustion as the oil will not have to be heated to as high a temperature to do the same amount of cracking due to the fact that the carbon is not permitted to collect in the bottom of the still and there insulate the oil from the heat of the furnace. The simplicity of the apparatus and the advantages which it presents in the way of increased heat and economical operation make it very desirable from many viewpoints.

In positioning the collector plate in the still it is not essential that the plate be inclined as a horizontal plate will supply the same collecting surface and permit the same amount of vaporization as an inclined plate. It is true that the inclination slightly assists in drawing off the residuum but this detail is not vital.

Another feature of importance is the length of the upturned end of the collector plate. If this upturned portion extends practically to or near the surface of the oil in the still or vaporizing chamber, the heavy

residuum and precipitated carbon will be prevented from backing up into the bottom of the still; also a lower level may be maintained in the vaporizing portion of the still which would reduce materially the amount of oil maintained at one time therein. By this construction there is maintained at all times a solid body of reflux and raw oil in the lower portion of the still or that portion to which the greatest amount of heat is subjected. This oil as it rises in a column at the end of the chamber adjacent the upturned extension of the collector plate overflows into the vaporizing portion of the still and the conversion or vaporization taking place in that portion will restrict the greater part or substantially all of the carbon deposition to the surface of the collector plate.

I claim as my invention:

1. A process for cracking hydrocarbon oil, consisting in converting the oil at a cracking temperature in a reacting chamber, dephlegmating and condensing the generated oil vapors, returning the reflux and causing it to be introduced and flow through the zone of highest temperature in said reacting chamber, circulating the oil to promote conversion in the upper part of said chamber and collecting the precipitated carbon in the interior of the chamber and out of contact with the lower heated portion thereof.

2. A process for cracking hydrocarbon oil, consisting in converting the oil at a cracking temperature in a reacting chamber, dephlegmating and condensing the generated oil vapors, returning the reflux and causing it to be introduced and flow through the zone of highest temperature in said reacting chamber, circulating the oil to promote conversion in the upper part of said chamber and collecting the precipitated carbon in the interior of the chamber and out of contact with the lower heated shell portion of said chamber and drawing off the residual substance.

3. A process for cracking hydrocarbon oil consisting in converting the oil at a cracking temperature in a partitioned reacting chamber, charging the oil to the portion subjected to the highest temperature, circulating the heated oil to a vaporizing portion, dephlegmating and condensing the generated vapors, collecting the precipitated carbon out of contact with the lower heated portion of said reacting chamber and drawing off the residual substance with substantial quantities of said precipitated carbon.

4. A process of cracking petroleum oil, comprising introducing oil to a converting chamber, in causing the oil introduced to said chamber to pass lengthwise thereof beneath a horizontal baffle, and then around said baffle to the upper portion of the chamber, in collecting on said baffle carbon

- precipitated during vaporization of the oil without allowing said carbon to contact with the heated wall of the conversion chamber, in withdrawing said carbon accumulating on said baffle, in discharging vapors from said conversion chamber to a dephlegmator, and in delivering reflux condensate with the raw oil to said conversion chamber beneath the baffle therein.
- 10 5. The process of cracking hydrocarbon oil, comprising introducing oil to a cracking still, in causing the oil in the still to travel lengthwise thereof beneath a baffle and then into the upper portion of the still to be subjected during a long course of 15 travel to the maximum heating temperature, in collecting on said baffle precipitated carbon and heavy residue resulting from the cracking of the oil without allowing said residue to deposit upon the heated walls of 20 the still and to prevent it from mixing with the charging oil, in withdrawing said residue accumulating on the baffle, and in continuously introducing raw oil to the still beneath the baffle.

CARBON P. DUBBS.
